UNITED STATES PATENT OFFICE.

ERNST OSCAR NEBEL, OF PHILADELPHIA, PENNSYLVANIA, ASSIGNOR TO OSCAR NEBEL CO., INC., OF HATBORO, PENNSYLVANIA, A CORPORATION OF PENNSYLVANIA.

DESIGN FOR A STOCKING.

Application filed December 20, 1926. Serial No. 20,096. Term of patent 7 years.

To all whom it may concern:

Be it known that I, ERNST OSCAR NEBEL, a citizen of the United States, residing in Philadelphia, Pennsylvania, have invented a new, original, and ornamental Design for a Stocking, of which the following is a specification, reference being had to the accompanying drawing, the single figure of which illustrates a stocking embodying my new design as applied to the limb of a wearer.

I claim:

The ornamental design for a stocking substantially as shown.

ERNST OSCAR NEBEL.
